METHOD AND APPARATUS FOR APPENDAGING POTTERY WARE

William J. Miller, Swissvale, and Ashley J. Reek, Carrick, Pa., assignors to Miller Pottery Engineering Company, Swissvale, Pa., a corporation of Pennsylvania

Application January 27, 1943, Serial No. 473,670

4 Claims. (Cl. 25—129)

1

This is a continuation in part of our co-pending application Serial No. 392,276, filed May 7, 1941, and it has to do with apparatus for appendaging pottery ware, particularly the mold which is employed to form the appendage.

More particularly, the present invention has to do with the sprue or that portion of the solidified material which remains in the filling opening after the appendage has set up and the problem of removal from the remainder of the appendage without tearing out material forming the appendage. The object is to obtain a clean break close to the surface of the appendage requiring little or no sponging or fettling to remove the traces thereof.

In the drawings:

Fig. 1 is a view showing a casting unit with the rear mold section removed illustrating how the appendage is cast and united to the prefabricated ware.

Fig. 2 is a fragmentary section showing the restricted passage between the mold cavity and the filling opening.

Fig. 3 is a fragmentary section looking down on top of the restricted passage of Fig. 2.

Fig. 4 is an elevation of a mold half illustrating another form of filling opening.

Fig. 5 is a sectional elevation through the center of the mold with the two halves in closed relation.

Fig. 6 is an enlarged sectional view showing the slit.

Fig. 7 is a sectional view illustrating the fin-like juncture between the sprue and the appendage.

Fig. 8 shows how the sprue of Fig. 7 is broken away from the appendage.

Fig. 9 is a plan view of a mold section and rigid hinge plate on which the same is mounted.

Fig. 10 is an elevation of one section of a portable mold showing a modified form of pouring hole and gate.

Fig. 11 is a top plan view of the complete mold, of which one section is illustrated in Fig. 10.

Fig. 12 is a fragmentary view showing how the gate may be filleted to avoid the production of a sharp edge at the juncture of the sprue with the appendage.

With reference to Fig. 1, an appendage casting unit is shown which includes a base 1 and a thruster 2 fully described in our co-pending application and therefore not described in detail here. The thruster 2 is actuated by mechanical linkage 3 to press the wall of an inverted piece of prefabricated pottery ware 4 against the con-

2

toured ware receiving surface 5, Fig. 9, of a portable mold, Figs. 1, 2 and 3, in leakproof sealed relation. The portable mold which comprises two mating sections 6 and 6a is hingedly mounted on a hinge pin 7 and is opened and closed mechanically in the manner described in our co-pending application. Fluid slip is fed to the mold through a rubber nozzle 8 fitted into a pipe 9 leading to a source of supply of fluid slip and the appendage, in this instance a cup handle, is cast in inverted position.

Slip entering the filling hole 9 of the mold passes into the molding cavity through a gate in the form of a narrow reduced passage 10 to one side and at the bottom of the hole having the proportions of a slit, see Figs. 2 and 3, the filling hole being of such capacity that it will hold a reserve supply of slip to be fed to the molding cavity as the appendage shrinks and solidifies. Since the flow of slip through the outlet 15 of the molding cavity is blocked by the ware, the appendage becomes attached to the ware as it solidifies, a permanent bond of high mechanical strength being formed.

The material remaining in the filling hole 9 and the slit 10 after the appendage has solidified forms a sprue 11, Fig. 7, which is attached to the underside of the appendage by a portion 12 of low mechanical strength or a weakened portion. When the sprue is detached, it will break through the weakened portion at substantially the level of the surface of the appendage or slightly thereabove, as illustrated in Fig. 8. If a slight prominence 14 remains on the appendage, this may be removed by sponging or fettling. Sometimes the sprue will break off flush with the surface of the appendage in which case only the roughened surface need only be rubbed over with a sponge to smooth off the blemish. A sprue connected or attached to the appendage by a weakened portion will break off without tearing out the material of the appendage and leaving a pit or cavity therein which cannot be repaired or erased by sponging. Considerable ware is rendered second or third grade by becoming pitted in the manner described and while the pit is in a concealed location, it nevertheless is discernible when the cup is raised.

The slit 10 at the bottom of the hole 9 preferably communicates with the molding cavity at the uppermost zone thereof in order that air entrapment will be minimized and complete filling of the mold assured. Of course, in actual practice, the seal between the wall of the ware and the contoured surface 5 of the mold is not en-

tirely perfect due to surface irregularities and air will escape therethrough. As soon as the liquid slip reaches the juncture, the solid constituents immediately plug the crevice so that the slip does not leak out.

The gate or slit 10 is illustrative of only one form of passage which will produce a weakened bond between the sprue and appendage. Other shapes or forms of gate than that described may answer the purpose and therefore we do not desire to be limited to this specific shape or form of gate illustrated. The dimensions of the gate should be such that it will not clog as long as the clay slip will flow. Of course, when the material solidifies, all flow through the gate ceases. The bond between the sprue and appendage should also be strong enough to support the weight of waste material forming the sprue when the mold is opened. Sometimes the sprue has a liquid center and premature breakage would spatter the ware which is not desired.

The sprue may be removed from the appendage by knocking it sidewise along the line of juncture with the appendage, Fig. 8, or it may be pinched lightly between the thumb and index finger and twisted.

A method of removing the sprue without touching the same with the fingers is to grasp the cup securely in one hand while it rests on the support 1 and then lift it clear and snap off the sprue by flipping the cup and then abruptly halting it. This causes the sprue to snap off of its own momentum across the weakened portion. This is usually done over a receptacle into which the waste material is thrown. This method speeds up the process of removing the sprue by eliminating excess manual handling.

In Figs. 4, 5 and 6 is shown a separable mold having a pouring hole 15 of globular or spherical shape whose inlet 16 may be circular or elliptical. This form of pouring hole produces a sprue of balanced design less apt to crack off prematurely when the mold is opened. Furthermore, being of globular or spherical shape, there are no crevices or sharp corners for the clay to stick in and the clay slip in the cavity will tend to shrink uniformly from the wall thereof. Having an inlet 16 which is small in proportion to the area of the hole 15, only a small portion of the contents is exposed to atmosphere. This retards setting up in the sprue before the appendage solidifies.

It will be understood that the wall of the holes 9 or 15 may be treated or impregnated with oil, wax, gum, shellac or other preparation which will retard the absorptive characteristics of the plaster of which the wall is formed in order that the sprue will remain fluid longer than the appendage and thus capable of supplying additional material to the appendage cavity as solidification sets in. This treatment may also be administered to the walls of the gate 9 or slit 17, Fig. 5, which is formed at the bottom of a passage 18 communicating with the spherical hole 15. The sprue thus formed has the shape of a ball supported on a stem attached to the appendage by a weakened portion as at 12, Fig. 7. The lower wall 19 of the passage 18 preferably tapers into the slit. The gate 17 communicates with the mold cavity at a point below the uppermost limits of the inverted mold cavity. We have found that this location is also satisfactory and that little or no air entrapment results. The volume of clay slip which the hole 15 will hold will produce sufficient static head to fill the appendage cavity completely. Of course, the static head in the supply pipe 9 is

primarily responsible for filling the cavity to its limit and driving out the air.

The mold of Figs. 4, 5 and 6 is made up of separable sections each of which has hinge formations 20 with grooves 21 to fit the hinge pin 7. A spring clip 22, Fig. 11, may be used to clamp the mold sections together. This type of mold may be used with automatic mold opening and closing machinery or may be opened by hand if provided with the friction roller devices 23 or similar appurtenances such as illustrated in connection with the mold of Fig. 11 which stand out at an angle from the body of each section on opposite sides of the mold and are adapted to be engaged and pressed toward one another to spring the mold open in an obvious fashion.

In the mold of Figs. 10 and 11, the same general principles of construction of the pouring hole and gate are retained, however, the pouring hole 24 herein is enlarged and cylindrical or elliptical in shape and may taper toward the base or may have a straight side if desired. The bottom of the hole has a pronounced taper as at 25 leading into the slit or gate 26 to the molding cavity. In this form of pouring hole, the gate is directly below the pouring hole whose gate is near the top of the molding cavity. Otherwise, the mold is the same as that shown in Figs. 4, 5 and 6, and is notched out at 25 at the rear around the hinge pin in order that the sections may pivot on the pin.

Thus, the present invention also contemplates a method of appendaging pottery ware wherein the mold and prefabricated ware are first brought together with the outlet 26 facing the wall of the cup and then slip is poured or piped into the pouring hole and discharged into the cavity through a reduced inlet or passage to form an appendage having a sprue attached thereto by a weak portion. After the appendage is solidified, the sprue is detached by breaking it off, the weak portion giving way and permitting a clean separation substantially flush with the surface of the appendage.

Figure 9 shows a mold section representative of any one of those previously described wherein the hinge formations 20 may be omitted and a metal backing 28 with a hinge formation 29 substituted therefor. This type of composite mold is shown in Fig. 1 and the two pieces of the section may be joined by casting the plaster portion on the metal portion. When the plaster wears out, it is simply knocked off and a new plaster section cast on the hinge plate. Obviously the plaster mold may be cast separately and attached to the hinge plate by screws.

In Fig. 12, we have shown how the gate may be filleted, as at 30, in order to eliminate a sharp edge at the juncture of the sprue with the appendage. The object is to insure that the sprue will break off above the surface of the appendage and not tear a hole in the appendage. It will be understood that the fillet may or may not be employed, as desired.

In snapping off the sprue without touching it by hand, the factor of inertia is involved due to the property of the sprue to continue its motion and snap off when the motion of the ware is arrested. Therefore, we prefer to refer to this operation as one wherein the sprue is snapped off by inertia.

Having thus described our invention, what we claim is:

1. A mold for casting an appendage on prefabricated potteryware comprising, a separable

body having a ware engaging surface contoured to fit the exterior surface of the ware, a molding cavity in which the appendage is formed having an outlet through the ware engaging surface and a pouring passage through which casting slip is poured into the molding cavity formed for producing a waste piece joined to the appendage by an elongated neck that is substantially narrower than either the appendage or the waste piece and provides a rupture area having less resistance to breakage than either the appendage or the waste piece.

2. A mold for casting an appendage on prefabricated potteryware comprising, a separable body having a ware engaging surface contoured to fit the exterior surface of the ware, a molding cavity in which the appendage is formed having an outlet through the ware engaging surface and a pouring passage through which casting slip is poured into the molding cavity formed for producing a waste piece joined to the appendage by an elongated neck along the seam line between mold sections that is substantially narrower than either the appendage or the balance of the waste piece and may be broken off flush or immediately above the surface of the appendage when pressure is exerted on the waste piece across the narrow dimension.

3. A mold for casting an appendage on prefabricated potteryware comprising, a separable 30

body having a ware engaging surface contoured to fit the exterior surface of the ware, a molding cavity in which the appendage is formed having an outlet through the ware engaging surface and a pouring passage through which casting slip is poured into the molding cavity formed with an elongated slit at the bottom of the passage that is substantially narrower than the remainder of the pouring passage or the molding cavity for producing a waste piece joined to the appendage by a rupturable elongated neck that is substantially narrower than either the appendage or the waste piece.

4. In the appendaging of prefabricated potteryware, the method which comprises slip casting an appendage against the exterior surface of the prefabricated ware and forming a waste piece joined thereto by an elongated neck that is substantially narrower than the appendage or the remainder of the waste piece, the waste piece above the neck having sufficient mass to cause it to snap off by inertia and, after the cast has been made, removing the ware with the appendage and waste piece attached thereto from the mold and moving the ware in such a manner as to break the restricted neck across the narrow dimension by the inertia of the waste piece.
